UNITED STATES PATENT OFFICE

2,078,850

GOVERNOR

Addison C. Hoof, Hinsdale, Ill.

Application June 20, 1935, Serial No. 27,577

13 Claims. (Cl. 137—152)

My invention relates to improvements in governors and similar devices.

My invention relates more particularly to improvements in governors for gasoline engines and particularly to the type where an unbalanced valve is inserted in the intake manifold and the closing movements thereof under the forces created by the cylinder displacement at different loads for a desired speed are balanced by a spring resistance.

The principal object of my invention is to provide an improved type of governor construction capable of more accurate governing action than any devices of the prior art.

15 A further object of my invention is to provide an improved governor of the type described that is extremely simple in construction, one which is easily and simply installed and will not easily become broken or out of order. A further object of my invention is to provide an improved adjusting means for governors of the type described.

20 A further object is to provide improved adjusting means whereby the entire governor assembly may be adjusted about the governor valve.

25 A further object of my invention is to provide an improved construction whereby the plate upon which the governor mechanism is assembled may be adjusted within the governor.

30 Other objects and advantages will be more apparent from the following description wherein reference is had to the accompanying two sheets of drawings upon which:

Fig. 1 is a side view of my improved governor with the cover plate removed;

35 Fig. 2 is a similar view thereof, showing the plate and all parts assembled thereon in a changed position;

Fig. 3 is a vertical sectional view of the governor taken generally on the lines 3—3 of Fig. 1; 40 and

Fig. 4 is a similar section through the conduit and valve portion taken generally on the lines 4—4 of Fig. 3.

45 My improved governor may be constructed of a pair of aluminum die castings 10 and 12 which are suitably bolted together to form a governor body and a housing respectively. The body 10 may be provided with suitable bolt openings 14 and 16 so that the same can be fastened in the 50 intake manifold of an automotive engine. The body 10 is also formed with a square passageway 18 adapted to be aligned with the passageway in the intake manifold conduit. An offset valve plate 20 is adapted to be positioned in the passageway 18 and is mounted upon a suitable shaft

22 which is journaled in suitable ball bearing members 24 and 26 positioned in the openings 28 and 30 in the governor body 10. It will be noted that the shaft has a flattened portion 30 upon which the valve plate is fastened, to which the 5 plate is secured by suitable screw members 32. The shaft is adapted to be held against lateral movement by a suitable locking ring 34 fastened over a reduced shoulder 35 adjacent the ball bearing member 26. A gasket ring 36 positioned 10 in the opening 38 prevents air from being drawn through the housing 12 to the passageway 18 as will be more clearly explained hereinafter. The ball bearing member 24 is adapted to be held in position by a spring washer member 38 and the 15 end of opening 28 is adapted to be closed by a similar spring washer member 40.

20 The shaft 22 may extend through an opening 42 in the governor housing 12 through a suitable bushing member 44 which is an enlarged portion positioned in the opening 30. The shaft 22 may extend through a plate member 46 and have an arm 48 secured to its outer end. The arm 48 may have a pin 50 in the end thereof upon which a roller member 52 is mounted. The 25 roller member 52 is adapted to engage the end of a multiple leaf spring 54 that has its one end fastened in a clamp or support member 56. The support member 56 has a stud portion 57 extending into a suitable opening 58 in the plate 46, 30 within which the same is rotatably mounted. The support 56 is formed upon one side with a segmental gear portion 59 that is adapted to mesh with a worm 60. The worm 60 may have a reduced portion 61 journaled in a boss 62 formed 35 in the plate 46 and its other end 63 journaled in a similar boss 64 formed in the plate 46. The end 63 may be formed with a screw driver slot 65 so that the worm may be rotated in this manner. The worm is also provided with an enlarged portion 67 within which a pair of cross bores 68 are provided for the purpose of permitting rotation of the worm by inserting a pin 40 in the bores and rotating the same.

45 As thus far described the governor may be similar to that shown in my recently issued Patent Number 1,999,758. However, in order to provide a wider range of operation and a more effective means of adjustment for the governor setting, I have mounted the spring 54 and spring 50 support 56 upon the plate member 46.

The plate member 46 is adapted to be mounted against the inside wall 70 of the governor housing 12. The plate may have an opening 71 through which the bushing 44 of shaft 22 extends 55

and it may be rotatably mounted upon this bushing. The plate 46 may be formed with an arcuate slot 72 through which a screw member 73 is adapted to pass and engage in a tapped opening in the wall 78 of housing 12. The screw member is provided for the purpose of holding plate 46 against wall 78 of the housing.

The plate 46 may be formed with limit stops 74 and 76 for the purpose of defining the travel of the arm or lever 48. The plate may be further formed with a segmental gear portion 78 adjacent one end thereof adapted to engage a worm 80. The worm 80 is formed with a reduced end portion 82 journalled in a suitable pass in the housing 12 and provided at its opposite end with an enlarged head portion 84 formed with the end slot 86. The slot 86 is adapted to be engaged by the end of a lock tumbler 88 suitably mounted in the housing and providing means for adjusting the position of plate 46 from the exterior of housing 12. The cover 90 for the housing 12 is adapted to be locked into position in the annular groove 92 of housing 12 and is provided for this purpose with a downwardly depending lug 94 formed with an opening 96 through which the barrel of lock 88 is adapted to pass. This construction is similar to that shown in my issued Patent Number 1,966,722.

With the construction which I have shown and described it will be obvious that in order to secure a setting of the governor to operate to close off the supply of fuel at a predetermined speed, this can be accomplished by rotating the plate 46 clock-wise or counter clock-wise as desired to increase or decrease the governing speed. In view of the fact that by changing the position of the support 56, the tension of the spring member 54 is shown and it can be seen that it is highly desirable to always keep the same proportionate tension upon the spring 54 and the only method by which this can be accomplished is by rotating the entire assembly or plate 46. With this construction, it will be obvious that if a governor is operating accurately at a given speed that the setting may be changed by rotating the plate 46 and the same accurate functioning hereby secured to any other speed.

While I have illustrated and described a specific embodiment of my invention incorporating a multiple leaf spring, it will be obvious that various different types of springs or other resistance means may be employed without departing from the spirit of this invention and I contemplate that changes and modifications may be made in the actual details shown and I do not desire to be limited in any particular; rather, what I desire to secure and protect by Letters Patent of the United States is:

1. In combination with the intake manifold of a gas engine, a shaft rotatably mounted in said manifold, an unbalanced valve fixed to said shaft in said manifold, a crank arm fixedly secured to the outer end of said shaft, a housing, a support, a multiple leaf spring mounted on said support for opposing the movement of the crank arm, a backing plate mounted in said housing, and means for adjusting the position of said backing plate, said means including a worm member, a key means for adjusting said worm, said leaf spring and support adapted to be adjustably mounted on said backing plate.

2. In combination with the intake manifold of a gas engine, a shaft rotatably mounted in said manifold, an unbalanced valve fixed to said shaft in said manifold, a crank arm fixedly secured to

the outer end of said shaft, a housing, a backing plate mounted therein, a support mounted thereon, resistance means mounted on said support for opposing the movement of the crank arm, adjusting means for said resistance means, said adjusting means and said support for said resistance means mounted on said backing plate and means comprising a worm and rack sector for adjusting the position of said backing plate.

3. In combination with an unbalanced throttle valve, means for resisting the closing movement of said valve comprising a leaf spring, a rotatably mounted block for holding one end of said spring, a screw for securing and adjusting said block back and forth in rotative position to regulate the tension of said spring and a backing plate, said leaf spring, said rotatable block and said screw member being mounted on said backing plate.

4. In combination with an unbalanced throttle valve, means for resisting the closing movement of said valve comprising a leaf spring, a rotatably mounted block for holding one end of said spring, a screw for securing and adjusting said block back and forth in rotative position to regulate the tension of said spring, a backing plate, said leaf spring, said rotatable block and said screw member being mounted on said backing plate and means for adjusting the position of said backing plate.

5. In combination with a throttle valve, means for resisting the closing movement of said valve comprising a rotatably mounted block, a leaf spring rigidly mounted on said block and projecting laterally therefrom, said spring adapted to resist the closing movement of said valve, a segmental gear member secured to said block, a screw member cooperating therewith to adjust said block, a plate, said block mounted upon said plate and means associated with said plate for changing the relative position thereof.

6. In combination with a throttle valve, an arm extending therefrom, means for resisting the closing movement of said valve comprising a rotatably mounted block, a leaf spring rigidly mounted on said block and projecting laterally therefrom, said spring resisting the closing movement of said valve by engaging said arm, a segmental gear member secured to said block, a screw member cooperating therewith to adjust said block, a plate, said block mounted upon said plate and means associated with said plate for changing the relative position thereof.

7. A governor comprising a conduit portion adapted to be inserted in the intake manifold of a gas engine, an unbalanced valve mounted in said conduit, a shaft therefor, an arm secured to said shaft, means for resisting the closing movement of said valve comprising a rotatably mounted block, a leaf spring rigidly mounted on said block and projecting laterally therefrom, said spring resisting the closing movement of said valve by engaging said arm, a segmental gear member secured to said block, a screw member co-operating therewith to adjust said block, a plate, said block mounted upon said plate and means associated with said plate for changing the relative position thereof.

8. In combination with a throttle valve, an arm extending therefrom, means for resisting the closing movement of said valve comprising a rotatably mounted block, a leaf spring rigidly mounted on said block and projecting laterally therefrom, said spring resisting the closing movement of said valve by engaging said arm, a seg-

mental gear member secured to said block, a screw member co-operating therewith to adjust said block, a plate, said block mounted upon said plate and means associated with said plate for changing the relative position thereof, said means comprising segmental gear means formed on an edge of said plate and a key operated worm in engagement therewith.

9. In combination with a throttle valve, an arm extending therefrom, means for resisting the closing movement of said valve comprising a rotatably mounted block, a leaf spring rigidly mounted on said block and projecting laterally therefrom, said spring resisting the closing movement of said valve by engaging said arm, a segmental gear member secured to said block, a screw member co-operating therewith to adjust said block, a plate, said block mounted upon said plate and means associated with said plate for changing the relative position thereof, said means comprising segmental gear means formed on an edge of said plate and a worm in engagement therewith.

10. In combination with an unbalanced throttle valve, means for resisting the closing movement of said valve comprising a leaf spring, a rotatably mounted block for holding one end of said spring, a screw for securing and adjusting said block back and forth in rotative position to regulate the tension of said spring and a backing plate, said leaf spring, said rotatable block and said screw member mounted on said backing plate, said backing plate having an arcuate slot adjacent one edge, a pin extending through said slot and means for rotating said backing plate within limits set by said slot and pin.

11. A governor comprising a housing, a con-

duit in said housing, a rotatably mounted shaft, a throttle valve and a crank arm fixedly secured to said shaft, said valve mounted in said conduit, a support, a leaf spring mounted upon said support contacted by the outer end of said crank arm, a backing plate adjustably mounted in said housing, a worm for adjusting said plate mounted in said housing, key means for actuating said worm, said support and leaf spring mounted upon said backing plate and capable of adjustment thereon.

12. A governor comprising a housing having a conduit therein, a rotatively mounted shaft extending through said conduit, a throttle valve and a crank arm fixedly secured to said shaft, said valve mounted in said conduit, said crank arm in said housing, a support, a leaf spring mounted upon said support contacted by the outer end of said crank arm, a backing plate, said support and leaf spring mounted upon said backing plate, means for adjusting the position of said backing plate including a lock cylinder and a cover for said housing locked on by said lock cylinder.

13. A governor comprising a housing having a conduit portion adapted to be inserted in the intake manifold of a gas engine, an unbalanced valve mounted in said conduit, a shaft therefor, said shaft extending into said housing, a plate member mounted in said housing, a lever on said shaft member, spring means for resisting the movement of said lever mounted on said plate, means for adjusting the position of said plate including a lock cylinder, a key therefor and a housing cover secured in position by said lock cylinder.

ADDISON C. HOOF.
